SUSPENDED CEILING SYSTEM AND
METHOD FOR INSTALLING THEREOF

FIELD OF THE INVENTION

The present invention relates to suspended ceiling systems comprising a plurality of ceiling tiles and a grid of profiles for supporting the plurality of ceiling tiles, the suspended ceiling system being adapted for instance for use in offices or public buildings etc. The invention further relates to a method for installing such a suspended ceiling system.

BACKGROUND ART

Suspended ceiling systems are used in many different types of buildings e.g. to lower the ceiling, to provide sound dampening, to facilitate mounting of light sources and other building equipment and to provide an aesthetically pleasing interior ceiling. Suspended ceiling systems, as the name implies, are attached to a supporting structure of some sort, such as the ceiling structure of the building. Suspended ceiling systems usually comprises a plurality of ceiling tiles and a supporting structure in form of a grid. The grid comprises profiles which support the ceiling tiles. The grid often comprises main profiles which are suspended to the ceiling structure of the building and transverse or cross profiles which are supported by the main profiles. The profiles usually have an inverted T-shape. The ceiling tiles may have sound-absorbing and/or sound-insulating properties in order to improve the acoustic environment of the room. In order to obtain a lightweight ceiling with satisfactory sound absorption, the tiles, for instance, may be made of a compressed fibre material such as mineral wool and especially glass wool. In addition to ceiling tiles, the profiles may also support various equipment such as lighting devices, ventilation equipment, inspection openings, detectors, cable trays, loudspeakers, signs, sprinklers etc.

The grid profiles are thus subjected to loads resulting from the weight of the profile itself along with the thereto attached tiles and equipment as described above. This causes deflection of the profiles, the deflection being proportional to the load subjected to the profile along with the span between the points where the profile is supported.

The deflection is measured as the distance between the profile and an imaginary straight line between adjacent suspension points when the profile is in its loaded condition.

Various standards for suspended ceilings, for example EN 13964 include requirements on the maximum deflection allowed. EN 13964 allows a deflection (for instance measured in mm) not exceeding the distance of the profile between the adjacent suspension points (for instance measured in mm) divided by 500 (for EN 13964 class 1), or for certain premises divided by 300 (EN 13964 class 2). However, the maximum deflection must be less or equal to 4,0 mm according to EN 13964 class 3.

To minimise the deflection and to increase the load which is exerted to a grid profile it is according to EP 2 562 323 A1 suggested to provide grid profiles which are upwardly curved. Such systems efficiently increases the amount of weight that the grid can carry without deviating from the deflection requirements described above.

The grid profiles are usually suspended from a supporting structure by means of some sort of suspension element such as a hanger. The hanger is connected to the grid usually through a hole in the profile. Each hanger is associated with a cost, not only for the hanger itself, but also in that it is relatively time consuming to fit. The presence of installa-

2

tions and/or building structures in the vicinity of the supporting structure may also cause problems, also referred to as clashing, when fitting the hangers. It is consequently always desired to reduce the number of hangers along the extension of the profiles to improve the cost efficiency of the suspended ceiling. Naturally however, this causes problems in terms of keeping the deflection of the grid profiles within the boundaries defined above.

SUMMARY OF THE INVENTION

In view of that stated above, the object of the present invention is to provide a suspended ceiling system ameliorating some of the problems with prior art. It is also an object to provide a method for installing a suspended ceiling system which is an improvement of prior art methods.

To achieve at least one of the above objects and also other objects that will be evident from the following description, a suspended ceiling system having the features defined in claim 1 and a method for installing a suspended ceiling having the features defined in claim 13 are provided according to the present invention. Preferred embodiments of the suspended ceiling system will be evident from the dependent claims.

More specifically, there is provided in a first aspect according to the present invention a suspended ceiling system comprising a plurality of ceiling tiles and a grid of profiles for supporting the plurality of ceiling tiles. The grid of profiles comprising at least a first and a second profile configured to be interconnected along a longitudinal axis, the first and second profile each comprising two laterally extending flanges and an upstanding web provided with a bulb at its free end. Each of the first and second profile has a curved extension and is configured to be installed such that it, in an installed and unloaded condition, bulges in an upward direction.

The suspended ceiling system further comprises a connection element arranged for mounting over a portion of the bulbs of the first and second profile at a joint between the first and second profile and a suspension element connectable to the connection element for suspension of the first and second profile in their interconnected state.

The ceiling system is thus allowed to be suspended from the joints between the profiles, which allows full utilization of the span of the curved extension of the profile while reducing the number of suspension points necessary for the system. The connection element further enables alignment of the first and second profiles in the joint. The suspension of the ceiling system using both a connection element and a separate suspension element provides flexibility, as it, depending on the application, allows either the connection element to be mounted to the profiles first or the connection element and the suspension element mounted to each other before the connection element is mounted to the profile.

The connection element may be arranged for snap fit mounting over the portion of the bulbs of the first and second profile. The snap fit mounting makes the attachment of the mounting elements to the profiles effortless and rapid and removes the need for tools.

The connection element may comprise two resilient legs which for said snap fit mounting are configured to straddle and retain the portion of the bulbs of first and second profile. The connection element is thus held in place by its interaction with the bulbs on the profiles. The connection element will further contribute to keeping the first and second profile aligned and held together.

The connection element may further comprise a bridging section having a first side from which the two resilient legs extend; and a protruding section provided with an opening arranged on a second side, opposing the first side, of the bridging section. The suspension element is configured to connect to the connection element by means of said opening. With the opening arranged on a protruding section on a side opposite that of the legs, conveniently places the opening such that it can be easily reached for connection of the suspension element.

The connection element may further comprise a protruding section provided with an opening, the suspension element being configured to connect to the connection element by means of said opening. With the opening arranged on a protruding section, it can be easily reached for connection of the suspension element.

Further still, the suspension element may comprise a hook member, the opening of the protruding section being configured to receive the hook member for connection of the suspension element to the connection element.

The suspension element comprises a free end provided with an opening, wherein suspension element is connectable to the connection element by means of a fastener inserted into the openings of the suspension element and the protruding section when the openings are aligned with each other.

The connection element may be made of a sheet metal material, which provides a low cost per unit and rapid production while providing sufficiently strong connection element for carrying the weight of the ceiling system.

Each of the first and second profile may have a joint end being provided with a tongue arrangement, the tongue arrangements of the first and second profile are configured for interlocking engagement in the interconnected state of the first and second profile. The profiles can thus be readily assembled and held together without having to use any tools or additional components.

In one embodiment, the first and second profile are configured to be interconnected solely by means of the connection element. The connection element thus not only serves as the anchor point from which the grid profiles are supported, but also as the interconnecting means which holds the profiles together. The assembly of the grid profiles is simplified as the profiles does not have to be assembled beforehand.

The first and second profile may, in the loaded and installed condition, be configured to be deflected such that they obtain an essentially linear extension. By application of a load on the grid of profiles, the upwardly bulging first and second profile will thus be straightened out by a controlled deflection and obtain an essentially linear extension. Deviations from this essentially linear extension, i.e. an additional deflection, may be allowed in accordance with various standards, such as EN 13964.

The curved extension of the first and second profile may be such that the maximum controlled deflection of each profile in the loaded and installed condition is in the range of 5-20 mm.

In a second aspect, a method is provided for installing a suspended ceiling system comprising a plurality of ceiling tiles and a grid of profiles for supporting the plurality of ceiling tiles. The method comprises:

Providing a first and second profile each comprising two laterally extending flanges and an upstanding web provided with a bulb at its free end. Each of the first and second profile has a curved extension.

Interconnecting the first and second profile such that they extend along a longitudinal axis, the interconnecting comprising snap fit mounting of a connection element over a portion of the bulbs at a joint between the first and second profile.

Suspending the first and second profile by connecting a suspension element to the connection element such that the interconnected first and second profile, in an unloaded condition, each bulges in an upward direction.

10 The installation of the suspended ceiling system is thus facilitated, as the connection element not only serves to interconnect the first and second profile but also to suspend the profiles.

15 Generally, all terms used in the claims are to be interpreted according to their ordinary meaning in the technical field, unless explicitly defined otherwise herein. All references to "a/an/the [element, device, component, means, step, etc]" are to be interpreted openly as referring to at least one instance of said element, device, component, means, step, etc., unless explicitly stated otherwise. The steps of any method disclosed herein do not have to be performed in the exact order disclosed, unless explicitly stated.

BRIEF DESCRIPTION OF THE DRAWINGS

25 The above, as well as additional objects, features and advantages of the present invention, will be better understood through the following illustrative and non-limiting detailed description of preferred embodiments of the present invention, with reference to the appended drawings, where the same reference numerals will be used for similar elements, wherein:

FIG. 1 discloses a perspective view of a suspended ceiling system.

30 FIG. 2 discloses a close up perspective view of a joint between two profiles of said ceiling system.

35 FIG. 3 discloses a perspective view of a connection element.

40 FIG. 4 discloses a plan view of a connection element before folding into final shape.

FIG. 5 discloses a side view of a connection element.

45 FIG. 6 discloses a view along the longitudinal axis of a grid profile.

FIG. 7 discloses a plan view of a suspension element.

FIG. 8 discloses a schematic outline of a method for installing a suspended ceiling system.

DESCRIPTION OF EMBODIMENTS

50 The present invention will now be described more fully hereinafter with reference to the accompanying drawings, in which currently preferred embodiments of the invention are shown. This invention may, however, be embodied in many different forms and should not be construed as limited to the 55 embodiments set forth herein; rather, these embodiments are provided for thoroughness and completeness, and fully convey the scope of the invention to the skilled person.

In FIG. 1, a suspended ceiling system 1 is shown. The ceiling system 100 is intended to be suspended from the ceiling structure and is configured to carry ceiling tiles (not shown) and various equipment, such as lights, cables, ventilation ducts etc., depending on the application at hand. The ceiling system 1 comprises a grid 100 of profiles, the profiles being interconnected such that the grid 100 is formed. The system 1 may comprise profiles of two types; profiles 40 extending in a first direction and transverse profiles 50 extending in a direction perpendicular to the first direction.

The profiles **40** are suspended to the ceiling structure by means of a connection element **10** and a suspension element **20** which is fitted in each joint between two profiles **40**. The suspension element **20** may be connected to a ceiling mount **30**, which may take the shape of a bracket or an angle iron of some sort which allows attachment of the suspension element **20** thereto.

The transverse profiles **50** are, when used, supported by the profiles **40**. The profiles **40**, and optionally the transversal profiles **50**, are arranged to form the grid **100** which has openings into which the ceiling tiles will fit.

The ceiling tiles generally functions to provide an appealing appearance to the suspended ceiling system **1**, to dampen sound and to hide the ceiling structure and possible building equipment that is arranged above the suspended ceiling system **1**. Such ceiling tiles may be formed in many different ways, the teachings herein are not limited to use with any particular type of ceiling tiles. However, in one embodiment, the ceiling tiles may be made of man-made mineral fibre, such as a compressed mineral fibre material. More specifically, the mineral fibre material may be mineral wool, especially glass wool. In addition to the mineral fibre material, the ceiling tiles may comprise a binder. The ceiling tiles may further comprise at least one surface layer.

As shown in FIG. 1, it is the profiles **40** which are suspended and that thus carries the weight of the tiles, of any possible transversal profiles **50** and of any eventual equipment fitted to the grid **100**.

In order to increase the load carrying capacity of the profiles **40**, they are provided with a curved extension and are configured to be installed such that they, in an installed and unloaded condition, bulges in an upward direction. The profiles **40** are also configured such that they in a loaded and installed condition, i.e. in response to a load, such as ceiling tiles, being applied to the profiles, are deflected such to obtain an essentially linear extension. The curved extension of the profiles **40** may be such that the maximum deflection of each profile **40** in the loaded and installed condition is in the range of 5-20 mm, whereby the profiles obtain the essentially linear extension.

The upwardly curved extension of the profiles will allow greater load to be placed on each profile **40** before it exceeds a certain regulated value for the downward deflection from the essentially linear extension. The deflection value may for example be defined depending on the distance *L* between the suspension points, for example measured in mm, divided by a factor of 300. I.e. a maximum allowed deflection could be defined as $f=L/300$. However, according to EN13964 class 3, the maximum deflection allowed is 4 mm, regardless of the distance between the suspension points.

The profiles **40** are configured to be interconnected such that a first and second profile of said profiles **40** can be attached to each other end to end along the longitudinal axis of the profiles **40**. In one embodiment, the connection element **10** is configured to solely interconnect the first and second profile **40**. The connection element **10** can thereby serve two purposes in that it not only provides an anchor point from in the joint from which the grid **100** can be suspended, but in that it also structurally connects each adjacent profile **40** in the grid **100**.

Arranging the connection elements **10** in the joints between the profiles **40** is also beneficial in that it reduces the amount suspension elements **20** required for suspending the ceiling system **1**. This saves time when installing the system **1**, facilitates the installation process and reduces cost of material.

Further, the reduced amount of suspension elements **20** also reduces the risk of clashing, i.e. that an installation or building structure in the area of the ceiling structure interferes with the desired position of a suspension element.

In one embodiment, as shown in FIG. 2, each of the first and second profile **40** has a joint end provided with a tongue arrangement **42**, the tongue arrangements **42** of the first and second profile **40** are configured for interlocking engagement in the interconnected state of the first and second profile **40**. The profiles **40** may thus be held together by the interaction of the tongue arrangement **42** on each profile **40**. In this embodiment, the connection element **10** may not necessarily contribute in any greater extend to the connection of the first and second profile **40**, but primarily provides an anchor point for connecting the suspension element **20**. However, the connection element **10** may be configured to provide a more substantial connection effect in addition to or instead of the interlocking effect of tongue arrangements **42** of the profiles **40**.

Each profile **40** is connected to at least two connection elements **10**. For prior art solutions, this means that each profile **40** is suspended by components corresponding to two suspension elements and two connection elements. In the context of the present disclosure, every two adjacent profiles **40** shares a connection element **10** and a suspension element **20**. This reduces the number of connection elements **10** and suspension elements **20** necessary. Further still, in the context of grid systems with profiles **40** which are curved as explained above, the connection element **10** aligns the ends of two adjacent profiles **40** in the joint between the profiles **40**. It also allows usage of the curvature of the profiles **40** over the entire length of the profiles **40**, as they are suspended in the ends of the profiles **40**.

FIG. 2 shows the system **1** in FIG. 1 in a close up view where a connection element **10**, a thereto connected suspension element **20** and an optional ceiling mount **30** are shown. The suspension element **20** is shown comprising an optional hook member **21**. The hook member **21** is in one embodiment configured to interact with an opening **15** of a protruding section **14** of the connection element **10**, which is shown in detail in FIG. 3. The opening is configured to receive the hook member **21** for connection of the suspension element **20** to the connection element **10**.

It is also shown in FIG. 2 how the connection element **10** is mounted in a snap fit manner over a portion of the bulbs **41** which are arranged on the profiles **40**. The interaction of the connection element **10** and the bulb **41** on the respective adjacent first and second profile **40** securely holds the profiles **40** in place. It should be noted however, that other means for mounting the connection element over the bulbs other than by snap fit mounting is conceivable.

Turning to FIG. 3, which discloses a detail view of the connection element **10** according to one embodiment. The connection element **10** in the embodiment shown, comprises two resilient legs **11, 12** which for the snap fit mounting are configured to straddle and retain the portion of the bulbs **41** of first and second profile **40**. The connection element **10** can thus be mounted simply by pressing the connection element **10** onto the first and second profile **40**, the interaction between the legs **11, 12** and the bulbs **41** will securely support the first and second profile **40**.

As can be further seen in FIG. 3, the connection element **10** may comprise a bridging section **13**. The bridging section **13** has a first side **16**, as can be seen in FIG. 5, from which the two resilient legs **11, 12** may extend. The optional protruding section **14** which is provided with the opening **15**

is arranged on a second side 17 of the bridging section 13, which can also be seen in FIG. 5. The second side 17 is opposite the first side 16.

What is further evident from FIGS. 3 and 4 is that the connection element 10 may be manufactured from sheet metal by means of punching and bending. Manufacturing the connection element 10 out of sheet metal provides benefits in terms of providing the desired resiliency in the material for the legs 11, 12 to be able to flex as necessary for the snap fit mounting to the profile 40. It is also preferred that the connection element 10 is manufactured out of metal, such as stainless steel or galvanized steel, as it must be able to sufficiently well withstand the heat during a potential fire. However, other materials are also considered depending on the application. The connection element 10 could be manufactured from a polymeric material, or from a composite material such as e.g. carbon composite.

FIG. 4 shows the connection element 10 blank material after punching but before bending into its final shape. As shown, the protruding section 14 may comprise two cut-out portions which are bent to form the protruding section 14, such that the openings 15 in the respective portion are aligned when the connection element 10 is finalized.

FIG. 5 shows the connection element 10 from the side. The opposite first and second side 16, 17 of the bridging section 13 is shown being formed by the middle portion of the connection element 10. The free end of each leg 11, 12 may comprise a lip section 18. Each lip sections 18 is bent such that it extends at an incline away from the lip section 18 on the opposite leg 11, 12. A wedge shaped recess is thus formed between the two lip sections 18 which facilitates mounting of the connection element 10 over the bulb 41 of the profile 40 such that the legs 11, 12 straddle the bulb 41 in a snap fit manner.

What is further shown in FIGS. 4 and 5 is that the connection element 10 may comprise locking members 19 which protrude from the free end of each leg 11, 12. The locking members 19 protrude towards the bridging section 13 such that the may form a securing engagement against the bulb 41. In one embodiment shown in FIG. 6, the bulb 41 of each profile 40 comprises a recess or groove 45 into which the locking member 19 will be arranged when the connection element 10 is fitted to the profile 40. The interaction between the locking member 19 and the groove 45 will prevent that the legs 11, 12 of the connection element 10 for some reason unintentionally to be released from the bulb 41.

In FIG. 6 it is further shown that each profile 40 comprises two laterally extending flanges 43 and an upstanding web 44 which is provided with the bulb 41 at its free end. The profile is preferably made in a roll forming operation out of a sheet blank of metal, for example steel. The sheet blank is fed between successive pairs of rolls that progressively bend, fold and form the sheet blank until the desired shape and cross section of the profile 40 is obtained. A beneficial profile and method for manufacturing the profile can be found in EP 2 562 323 A1. The teachings herein are however not limited to use with profiles being manufactured in any specific way or of any specific material, any profile having the essential features outlined in claim 1 will be suitable for use with the suspended ceiling system 1.

Turning now to FIG. 7 which shows a suspension element 20 according to one embodiment. In FIG. 7, the suspension element 20 is embodied as a strip of sheet material, preferably out of metal such as steel but other materials are also considered. The suspension element may comprise reinforcing ribs along the length of the element 20. The suspension element 20 may further comprise a free end 22 which is

provided with an opening 23. The suspension element 20 is connectable to the connection element 10 by means of a fastener inserted into the openings 23, 15 of the suspension element 20 and the protruding section 14 when the openings 23, 15 are aligned with each other.

In the embodiment where the protruding section 14 is formed by two cut-out portions, the free end 22 of the suspension element 20 could be configured to be arranged between the two portions of the protruding section 14 and then fastened with the fastener.

Alternatively, as mentioned above, the suspension element 20 may comprise a hook member 21 configured to cooperate with the opening 15 in the protruding section 14.

The suspension element 20 may further be provided with an additional opening 24 on the end opposite the free end 22. The additional opening 24 being configured to be attached to the ceiling mount 30 by means of a suitable fastener.

FIG. 8 shows a schematic outline of a method for installing a suspended ceiling system 1 as described above. The method comprises providing 1001 a first and second profile 40 each comprising two laterally extending flanges 43 and an upstanding web 44 provided with a bulb 41 at its free end. Each of the first and second profile 40 has a curved extension. The profile, as mentioned, does not need to be made from any particular material or by any particular process. The first and second profiles 40 are then interconnected 1002 such that they extend along a longitudinal axis. The interconnecting comprising snap fit mounting of a connection element 10 over a portion of the bulbs 41 at a joint between the first and second profile 40.

The first and second profiles 40 are then suspended 1003 by connecting a suspension element 20 to the connection element 10 such that the interconnected first and second profile 40, in an unloaded condition, each bulges in an upward direction.

It will be appreciated that the present invention is not limited to the embodiments shown.

The connection element may be formed in different ways. For instance, the protruding section need not be formed from bent cut-out portions but may constitute a top portion of a folded sheet metal material, wherein the two legs extend continuously from the top portion.

Several modifications and variations are thus conceivable within the scope of the invention which thus is exclusively defined by the appended claims.

The invention claimed is:

1. A suspended ceiling system comprising:
a plurality of ceiling tiles; and
a grid of profiles for supporting the plurality of ceiling tiles, the grid of profiles including at least a first profile and a second profile configured to be interconnected along a longitudinal axis, the first and second profiles each comprising two laterally extending flanges and an upstanding web provided with a bulb at a free end of the upstanding web,
wherein each of the first and second profiles has a curved extension and is configured to be installed such that each of the first and second profiles, in an installed and unloaded condition, bulges in an upward direction,
wherein the suspended ceiling system further comprises a connection element arranged for mounting over a portion of the bulbs of the first and second profiles at a joint between the first and second profiles, and
wherein a suspension element is connectable to the connection element for suspension of the first and second profiles in an interconnected state.

2. The suspended ceiling system according to claim 1, wherein the connection element is arranged for snap fit mounting over the portion of the bulbs of the first and second profiles.

3. The suspended ceiling system according to claim 2, wherein the connection element comprises two resilient legs which for said snap fit mounting are configured to straddle and retain the portion of the bulbs of first and second profiles.

4. The suspended ceiling system according to claim 3, in which the connection element comprises a bridging section having a first side from which the two resilient legs extend; and a protruding section provided with an opening arranged on a second side, opposing the first side, of the bridging section, wherein the suspension element is configured to connect to the connection element by means of said opening.

5. The suspended ceiling system according to claim 1, wherein the connection element comprises a protruding section provided with an opening and wherein the suspension element is configured to connect to the connection element by means of said opening.

6. The suspended ceiling system according to claim 5, in which the suspension element comprises a hook member, wherein the opening of the protruding section is configured to receive the hook member for connection of the suspension element to the connection element.

7. The suspended ceiling system according to claim 5, in which the suspension element comprises a free end provided with an opening,

wherein the suspension element is connectable to the connection element by means of a fastener inserted into the opening of the suspension element and the opening of the protruding section when the openings are aligned with each other.

8. The suspended ceiling system according to claim 1, wherein the connection element is made of a sheet metal material.

9. The suspended ceiling system according to claim 1, wherein each of the first and second profiles has a joint end provided with a tongue arrangement, wherein the tongue arrangements of the first and second profiles are configured for interlocking engagement in the interconnected state of the first and second profiles.

10. The suspended ceiling system according to claim 1, wherein the first and second profiles are configured to be interconnected solely by means of the connection element.

11. The suspended ceiling system according to claim 1, wherein the first and second profiles, in a loaded and installed condition, are configured to be deflected such that they obtain an essentially linear extension.

12. The suspended ceiling system according to claim 11, wherein the curved extension of the first and second profiles is such that the maximum deflection of each profile in the loaded and installed condition is in a range of 5-20 mm.

13. A method for installing a suspended ceiling system comprising a plurality of ceiling tiles and a grid of profiles for supporting the plurality of ceiling tiles, the method comprising:

providing a first profile and a second profile each comprising two laterally extending flanges and an upstanding web provided with a bulb at a free end of the upstanding web, wherein each of the first and second profiles has a curved extension, interconnecting the first and second profiles such that they extend along a longitudinal axis, said interconnecting comprising mounting of a connection element over a portion of the bulbs at a joint between the first and second profiles, and

suspending the first and second profiles by connecting a suspension element to the connection element such that the interconnected first and second profiles, in an unloaded condition, each bulges in an upward direction.
